UNITED STATES PATENT OFFICE

2,215,360

DRAIN OPENER

William C. Lundstrom, Spokane, Wash.

Application December 28, 1938, Serial No. 248,137

1 Claim. (Cl. 285—44)

This invention relates to a drain opener for sinks, tubs and similar devices, and has for the primary object the provision of a device of this character which may be readily applied to the mouth of a drain and to a faucet of the water system whereby the water pressure may be employed to dislodge any obstruction in the drain and to thoroughly flush the latter of any foreign matter, the device being self-sustaining after being applied and may be readily attached to either the hot or cold water faucets.

With these and other objects in view, the invention consists in certain novel features of construction, combination and arrangement of parts to be hereinafter more fully described and claimed.

For a complete understanding of my invention, reference is to be had to the following description and accompanying drawings, in which

20 Figure 1 is a side elevation, partly in section, illustrating a drain opener constructed in accordance with my invention and showing the same applied to a drain of a sink and connected to a faucet.

25 Figure 2 is a vertical sectional view illustrating the drain cup and its connection with a hose.

Figure 3 is a sectional view taken on the line 3—3 of Figure 2.

30 Figure 4 is a sectional view taken on the line 4—4 of Figure 2.

Figure 5 is a fragmentary vertical sectional view illustrating a fitting for connecting the hose of the device onto a faucet.

35 Referring in detail to the drawings, the numeral 5 indicates a substantially conical-shaped drain engaging member which includes a neck 6 having a bore 7 partly screw threaded to receive a screw threaded sleeve or fitting 8 employed for connecting to the neck 6 a hose 9 including the usual female type fitting 10. The sleeve 8 is offset exteriorly of the neck 6 to form a chamber in which is positioned a spider 11.

40 The substantially conical-shaped member 5 or cup has at its mouth a flange 12 provided with 45 a bevel face 13 presenting in the cup an internal shoulder 14. The member or cup 5 is reinforced by a metallic ring 15 positioned therein adjacent the flange 14.

45 The bevel face 13 of the flange 12, when the member 5 is detached, flares outwardly and is adapted to be brought in seated engagement with a wall 16 of a sink or like device 17 directly over a drain 18 by distending the same.

50 The member 5 is outwardly bowed above the flange 12 and the ring 15 larger in diameter than

the shoulder 14, said ring being fitted in the bowed portion of the member 5 whereby it is frictionally locked to the member above the shoulder 14 to drop down on said shoulder when said flange 12 is distended and retain the same 5 in distended position.

55 The spider 11 has threaded thereto a rod 19 terminating at one end in the form of a hook 20 to engage with the usual spider or similar device 21 located in the drain 18. The other end of the rod extends outwardly of the sleeve 8 and may be rotated for drawing the cup or member 5 tightly against the wall 16 of the sink or similar device so as to prevent air from entering the drain between the wall 16 and the cup or member. The sleeve 8 is then connected with the hose 9, the latter having at its other end a fitting 19 to connect with a faucet 20 so that water under pressure may be directed into the drain for dislodging an obstruction therein and 20 for flushing the drain of any foreign matter. With the cup or member 5 secured on the drain as described and the fitting 19 adapted to the faucet the device will be self-sustaining while in 25 operation.

It is to be understood that the cup or member 5 including the neck 6 is constructed of rubber or some other material suitable for the purpose so that the device will readily adjust itself to the wall of the sink over the drain when applied 30 thereto to prevent the escape of water when directed into the drain under pressure.

35 The fitting 19 is in the form of an elastic sleeve 22 which may be readily stretched over one end of the hose 9 and its opposite end is turned back upon itself, as shown at 23, to form a reinforcing flange. The latter-named end with the reinforcing flange 23 is adapted to be stretched over the nozzle or discharge end of the faucet so that the fitting will be self-sustaining on the faucet as 40 well as on the hose and can be easily removed from either when desired.

45 Through the use of this present device a drain can be flushed either by hot or cold water under pressure depending on which faucet the fitting 19 is adapted to.

50 It is believed that the foregoing description, when taken in connection with the drawings will fully set forth the construction and advantages of this invention to those skilled in the art to 55 which device relates, so that further detailed description will not be required.

Having thus described my invention, I claim:

55 A drain opener comprising a yielding cup member adapted for application to a wall of a sink,

or the like, over a drain opening and operative as a combination suction cup and suction pump, said member having an annular laterally extending flange around the mouth thereof forming a wide flat attaching rim on said mouth normally flaring outwardly for gradual application to said wall under downward pressure on the cup member to effect a suction grip by said member on said wall, said flange providing an annular internal shoulder in said member, a reinforcing ring loose in said member and surmounting said shoulder to hold said flange in shape when applied, a neck on said member internally threaded, a sleeve threaded in the said neck and protruding

therefrom, a spider in said sleeve confined therein, a rod threaded into the spider and having a hooked lower end for attachment to a fixed part in said drain, said sleeve having a threaded upper end for attachment to a hose line leading from a faucet, said flange being distensible to flex said rim flat against said wall, said ring being frictionally locked to the inner wall of said cup member above said shoulder for release under distension of said flange to drop down onto said shoulder when the flange is fully distended and retain said flange in such position. 5 10
